[57]

ABSTRACT

Apparatus for manufacturing multiple transformers simultaneously by winding several wire coils on bobbins and applying tape over each coil includes carriage mechanisms which are independently movable along three mutually perpendicular axes and orbitally about one of the axes. Separate drive mechanisms for each mode of movement include drive motors mounted on a stationary frame, thereby reducing the mass of the moving elements of the apparatus and permitting rapid changes in speed and direction of movements. Carriage-frame structural interlocks also provide low mass with rigidity to the carriage elements. A simple winding pitch adjusting mechanism, incorporating a drive lever with a variable pivot point, also forms part of the apparatus and also has a separate frame-mounted drive motor, as does a taping mechanism for applying tape over each wound coil. A group of bobbin-rotating spindles are connected to be driven by one of the frame-mounted carriage drive motors. The various mechanism of the apparatus are automatically operated in proper timed sequence according to programs provided for by a program-controllable card reader device and an automatic control system including a sequencing device in the form of a rotary, switch-actuating drum.

FIG-16

APPARATUS FOR DISTRIBUTING A STRAND

BACKGROUND OF THE INVENTION

This invention relates to apparatus for distributing a strand and, more particularly, to apparatus for winding one or more strands or wires onto a bobbin to form a wound article, such as a transformer.

In the manufacture of wound articles, e.g., multi-coil transformers, the performance of a number of relatively complex operations may be necessary. The required operations may include movements of a strand or wire guide along one or more of three mutually perpendicular axes so that the wire guide will place a segment of wire in proper position for winding onto a transformer bobbin. Such axial movement of the wire guide may also be utilized in order to distribute the wire longitudinally along the bobbin during winding. Additionally, the wire guide may be required to undergo orbital movement about one of the axes in order to wrap one or more turns of wire about a terminal of the bobbin. The bobbin may preferably be rotated during the winding operation through any desired number of turns of the wire to be wrapped. Further, winding pitch adjustments may have to be made during transformer manufacture. Wire cutting operation may also be required so that multiple, separate coils of wire may be wound on a transformer. Moreover, intermediate taping and tape severing operations may be utilized in order to provide electrical insulation between adjacent coils of wire.

Clearly, it is desirable to provide equipment for manufacturing articles, e.g., multi-coil transformers, having the capability of performing in controlled manner operations such as those just described. Preferably, such manufacturing apparatus should simply, effectively, reliably, rapidly and automatically carry out the intended tasks with a minimum of external supervision being required. The apparatus should also, preferably, be adapted to manufacture articles according to a number of different specifications, e.g., differing in numbers of windings, pitch of coils wound and the like.

SUMMARY OF THE INVENTION

An object of the invention resides in new and improved apparatus for distributing a strand, e.g., in order to wind one or more strands or wires onto a bobbin to form wound article, such as a transformer.

The invention contemplates apparatus including a plurality of mechanisms which cooperate to produce wound articles. Exemplary of such mechanisms are a carriage assembly mounting a strand guide to move along one or more of three mutually perpendicular axes and/or orbitally about one of the axes, independent drive facilities for moving the strand guide independently along each of the three axes and orbitally about the one axis, a bobbin rotating mechanism, a winding pitch adjusting mechanism, a wire cutting device and taping and tape severing facilities. Each of these mechanisms is to be operated in a predetermined time sequence under the regulation of automatic control apparatus. The automatic control apparatus, which may include a program-controllable device, is adapted to vary certain parameters, e.g., numbers of windings, pitch of coils wound and the like, in order that articles be formed according to a number of different specifications, e.g., as may be regulated by patterns of holes in

cards to be read sequentially by a card reader mechanism.

In order that rapid movements of the strand guide may take place to minimize transformer production time, the invention contemplates that the mass of the moving parts of the carriage assembly be minimized. Such minimization is achieved, in part, by mounting all drive and adjusting motors externally of the carriage assembly at fixed remote positions. At the same time, a rigid, light weight carriage structure is contemplated by mounting certain rigidity-maintaining carriage assembly elements so as not to move linearly with associated linearly-moved elements of the carriage assembly. Additionally, an economization in the number and complexity of carriage drive elements is achieved by operating certain elements of two linear axis drive mechanisms in timed sequence in order to provide orbital motion of the strand guide about the third axis and by utilizing simplified carriage shifting and detenting devices.

Another feature of apparatus constructed in accordance with the principles of the invention resides in a simple and effective winding pitch changing mechanism operable at selected times during manufacture of a transformer, e.g., so as to vary the pitch of different windings of a single transformer. This pitch changing mechanism is operated by simply controlledly altering the pivot point on a lever which forms part of one of the carriage assembly axial drive mechanisms.

These and other mechanisms of the apparatus, as contemplated by the invention, function in cooperative manner to simply, effectively, reliably, rapidly and automatically manufacture wound articles, such as transformers, while requiring a minimum of supervision and while permitting rapid alteration of product specification under automatic control.

BRIEF DESCRIPTION OF THE DRAWING

FIG. 1 is an isometric view, with parts broken away, illustrating apparatus constructed in accordance with the principles of the invention for winding five coils simultaneously and applying tape simultaneously over the coil windings during the manufacture of transformers;

FIG. 2 is an isometric view showing a completed transformer and a portion of one of five spindles upon which bobbins are supported during simultaneous winding and simultaneous taping operations of the apparatus of FIG. 1 to produce the completed transformer;

FIG. 3 is an isometric view of a bobbin prior to the simultaneous winding and simultaneous taping operations;

FIG. 4 is an isometric view, with parts broken away and with certain portions exaggerated in size for purposes of illustration only, showing various drive mechanisms for rotating the five spindles and for displacing several carriage members forming portions of the apparatus so as to move five wire guide members supported adjacent the spindles by the carriage members linearly along three mutually perpendicular axes, labeled, "X," "Y" and "Z," and orbitally about one of the axes;

FIGS. 5, 6 and 7 are enlarged and more detailed views of various portions of the illustration provided by FIG. 4;

FIG. 8 provides an enlarged and more detailed view of a portion of the illustrated of FIG. 4 and also depicts a portion of a taping carriage and taping carriage drive mechanism forming a part of the apparatus;

FIG. 9 is a vertical end view, with parts broken away, looking in a rearward Z direction and showing the spindles and some of the spindle drive members, as well as adjacent portions of the taping carriage;

FIG. 10 is an enlarged and more detailed view of portions of mechanisms associated with a Y axis drive mechanism illustrated in FIG. 4;

FIG. 11 is an enlarged and more detailed view of portions of a Z axis drive mechanism illustrated in FIG. 4;

FIG. 12 is an enlarged and more detailed view of a X axis detent mechanism partially illustrated in FIG. 4;

FIGS. 13A, 13B, 13C and 13D are vertical frontal views, looking in a rearward X direction, of portions of the taping carriage, one of the spindles and one of the wire guides, illustrating successive stages in the operation of various mechanisms associated with the taping carriage;

FIGS. 14A, 14B, 14C, 14D, 14E, 14F and 14G are circuit diagrams depicting successive portions of a control circuit for operating the apparatus, the entire circuit being formed by a vertical alignment of FIG. 14B beneath FIG. 14A, FIG. 14C beneath FIG. 14B, etc.;

FIGS. 15A and 15B constitute portions of a timing chart which may be utilized to program a sequence of operations of a number of switches through actuation by a rotary, switch-actuating drum, the chart indicating a sequence of machine operations provided by the sequence of switch operations; the entire timing chart if formed through a vertical alignment of FIG. 15B beneath FIG. 15A; and

FIG. 16 is a circuit diagram illustrating a drive motor control system which may be utilized with the control circuit of FIGS. 14A through 14G.

DETAILED DESCRIPTION

General Outline Of Coil Winding And Taping Apparatus

With reference to the drawing, FIG. 1 illustrates an apparatus constructed in accordance with the principles of the invention for operating upon five bobbins 21 (FIG. 3) simultaneously in the manufacture of transformers 22 (FIG. 2). Each completed transformer 22 will include a number of windings (e.g., five) of strands of wire 23 wound about a central, recessed area 24 of the bobbin. A section of tape 26 surrounds each of the windings, including the final winding. The bobbins 21 are composed of a plastic or other dielectric material, while the wire 23 is made of insulated copper or of any other suitable electrically conductive material. The tape 26 is composed of an adhesive-coated, dielectric material, e.g., a polyethylene terephthalate film sold commercially under the trademark "Mylar," effective to insulate the windings from each other and to provide desired electrical characteristics to the transformer.

Each segment of wire 23 which constitutes a winding of a transformer 22 has its opposite ends secured to two different electrically conductive terminal members 27 forming parts of the bobbin 21. The bobbin 21 preferably includes twice as many terminals 27 as the number of windings of wire to be wound to form a completed transformer 22. The apparatus, in order to manufacture the finished product shown in FIG. 2, is to

operate upon each bobbin 21 first to wrap a portion of wire 23 about a first terminal 27, next to wind a first segment of the wire 23 about the recessed area 24 of the bobbin, then to wrap several turns of the wire about a second terminal 27, thereupon to apply a section of the tape 26 about the first segment of wire 23 and sever the applied tape, and thereafter to wind and tape additional windings over the first winding in like manner, utilizing two new terminals 27 about which to wrap the opposite ends of each new winding. Excess wire segments extending between terminals and not constituting windings are later to be trimmed off in an additional operation not associated with the winding apparatus.

Five horizontally extending spindles 31 (FIGS. 1, 2, 4 and 9) are provided by the apparatus. Each spindle 31 includes a wire spring member 32 (FIG. 2) for mounting one of the bobbins 21 on the spindle, as shown in FIGS. 2 and 13A through 13D. A continuously rotatable, constant speed motor 33 (FIGS. 4 and 14A) is utilized to drive the five spindles 31 simultaneously through an eddy current clutch 33A and a spindles drive clutch 34 (FIGS. 4, 8, 9 and 14E). With the clutches 33A and 34 engaged, the motor 33 will rotate the bobbins 21 simultaneously about axes parallel to an X axis (FIG. 2) to wind segments of wire 23 about the recessed areas 24 of the bobbins. An eddy current brake 33B (FIG. 7) cooperates with eddy current clutch 33A to control the speed of rotation of an output shaft 35 forming part of a drive train to the clutch 34.

Five tubular wire guides 36 (FIGS. 1 and 13A) are mounted on a wire guide Z carriage 37. Each wire guide extends horizontally and perpendicularly toward a different spindle 31 to provide wire to be wound on a bobbin 21 carried by the spindle. Various drive mechanisms forming parts of the coil winding apparatus will move the wire guides 36 linearly along three mutually perpendicular axes and orbitally about one of the three axes. These motions will be achieved through movements of the Z carriage 37, an X carriage 38 and a Y carriage 39. The axes of linear movement are identified in various illustrations of the drawing as the X, Y and Z axes. Orbital movement will take place about the Z axis.

A prime reason for reciprocation of the wire guides 36 in an X direction will be to distribute the segments of wire 23 axially along the recessed areas 24 of the bobbins 21 during the winding operation. A main purpose for movement of the wire guides 36 along the Y direction will be to align each of the wire guides vertically with a selected terminal 27 in position for the wrapping of several turns of wire 23 about the selected terminal. Orbital movement of the wire guides 36 about the Z axis will then wrap the turns of wire 23 about each selected terminal 27. Displacement of the wire guides 36 along the Z direction, in addition to X and Y displacements, will be utilized to move the guides between a coil winding position, a terminal wrapping position and a wire anchoring position, as required.

The motor 33 and three additional motors 41, 42, 43 (FIGS. 4, 14B and 14C) are mounted in positions remote from the several wire guide carriages 37, 38, and 39 on various members of a fixed frame 44 of the apparatus. The motors 33, 41, 42, 43 provide the drive power necessary for the movements of the wire guides 36 linearly along the X, Y and Z axes and orbitally about the Z axis, respectively.

Additional mechanisms forming portions of the apparatus include an X axis rapid traverse mechanism 46 (FIGS. 4, 6 and 7), operated by the X axis drive motor 33, and an "X" axis winding pitch adjusting mechanism 47 (FIGS. 4 and 6), operated by an additional motor 48 (see also FIG. 14B). The winding pitch adjusting motor 48 is mounted externally of the various wire guide carriages 37, 38 and 39 at a remote position on the stationary frame 44 in similar fashion to the drive motors 33, 41, 42 and 43.

A taping carriage 51 (FIGS. 1, 8 and 13A through 13D), mounted for movement in the Z direction, carries mechanisms for applying sections of the adhesive-coated, dielectric tape 26 over each winding of wire 23. Movements of the taping carriage 51 along the Z axis are provided by drive mechanisms associated with a vertically mounted taping carriage motor 52 (FIGS. 8 and 14C). The motor 52 is mounted to the fixed frame 44 of the apparatus at a position remote from the taping carriage 51, as well as from the X, Y and Z carriages 38, 39 and 37, respectively.

Automatic control facilities, including a conventional program-controllable device, such as a card reader 56 (FIG. 1), a sequencing device, such as a rotary, switch actuating drum 57 (FIG. 14A), and various associated control circuits (FIGS. 14A through 14F), are utilized to perform a number of control functions upon the apparatus. For example, the sequencing device 57 and associated circuitry will operate the various drive mechanisms to regulate the X, Y and Z positions of the wire guides at all times, will adjust the winding pitch along the X axis whenever required, will govern the number of turns of wire in each winding of a transformer 22, will select proper terminals 27 for wrapping with a desired number of turns of wire and will operate the taping carriage motor 52 to perform a tape applying operation after each wire winding operation, all in accordance with instructions received from the program-controllable device 56 and its associated circuitry.

In order that the apparatus may function at a desirably high rate of product output, the apparatus must be capable of responding very rapidly to signals from the control system. For purposes of satisfying this requirement, the apparatus has been designed so that all of the various drive motors 33, 41, 42, 43, 48, 52 are mounted on the fixed frame 44 remotely of the various moving carriages 37, 38, 39, 51, as described above. As a result, the mass of each of the carriages is minimized to render substantially negligible the inertial resistance of the carriages to changes in momentum conditions required in the operation of the apparatus.

Various major mechanisms of the coil winding apparatus have now been set forth in outline form, in order to provide a basic understanding of the overall apparatus. The individual mechanisms will next be discussed in some detail.

The Z Carriage Drive Mechanism

The Z carriage 37 (FIGS. 1, 4 and 5) includes a vertical wire guide mounting bar 60, a wire guide support plate 61 which is carried by the mounting bar 60 and which supports the wire guides 36, and a pair of rod-like members 62 and 63 projecting rearwardly in the Z direction from opposite vertical ends of the support plate 61. The rods 62 and 63 are supported for movement along the Z axis by a pair of bearing assemblies 64

and 66, respectively. A follower plate 67, integral with the wire guide mounting bar 60, projects rearwardly in the Z direction intermediate the rods 62 and 63. A vertical slot 68 passes through the follower plate 67.

The Z axis drive motor 42 (FIGS. 4 and 11) is connected to rotate a drive shaft 71 when the motor is energized. The drive shaft 71 is mounted extending horizontally along the X direction toward the slot 68 in bearings (not shown) fixed to the frame 44 of the apparatus. An eccentric portion 72 (FIGS. 4 and 5) projects forwardly in the X direction at a forward end of the drive shaft 71 and passes perpendicularly through the slot. The vertical extent of the slot 68 is sufficient to permit all vertical, Y axis movements required of the wire guide mounting bar 60 without any contact occurring between the ends of the slot and the eccentric 72. The X direction length of the eccentric 72 is sufficient to maintain a portion of the eccentric within the slot 68 throughout the range of X direction movement which is to be imparted to the mounting bar 60. The arrangement is such that rotary movements of the shaft 71, through operation of the drive motor 42, will produce linear movements of the Z carriage 37 along the Z axis.

A pair of cams 73 and 74 (FIG. 11) are mounted to rotate with the shaft 71. A raised lobe 76 is located on cam 73 in a position 180° about the periphery of the shaft 71 from a raised lobe 77 on cam 74. A cam follower 78 is biased into contact with the cam 73 by a spring (not shown). The cam follower 78 is connected to actuate a switch 79 when lifted by the lobe 76. A cam follower 81 is biased into contact with the cam 74 by another spring (not shown). The cam follower 81 is connected to actuate a switch 82 when lifted by the lobe 77. The two switches 79 and 82 will function to sense the angular orientation of the shaft 71 and, therefore, the position of the eccentric 72 and of the Z carriage 37. Signals from the switches 79 and 82 (see also FIG. 14B) will act to terminate linear Z axis movements of the carriage 37 at desired forwardmost and rearwardmost carriage positions.

The follower plate 67 (FIGS. 4 and 5) will be moved vertically with respect to the vertically fixed shaft 71 during Y direction movements of the wire guide mounting bar 60. Thus, the vertical range of the contact between the eccentric 72 and the side walls of the slot 68 will be variable. Moreover, it may be convenient to locate the follower plate 67 on the wire guide mounting bar 60 at a position closer to one of the rods 62 and 63 than to the center, as shown in the depicted embodiment (FIGS. 4 and 5). It is necessary that structural integrity be maintained for the Z carriage 37 in spite of the variable, offset position of driving contact between the eccentric 72 and the side walls of the slot 68. Otherwise, the offset contact would tend to flex the Z carriage laterally, e.g., by driving the upper portion of the carriage along the Z axis ahead of the lower portion of the carriage. This would result in misalignment between the wire guides 36 and the spindles 31.

An equalizer shaft 86 (FIG. 5) has a pair of pinions 87 and 88 mounted at its opposite ends. The equalizer shaft is mounted within a tubular member 89 extending vertically between the bearing assemblies 64 and 66 which support the rod-like members 62 and 63. Each of the rods 62 and 63 has a toothed, rack portion 91 or 92 along its rearward portion. The tubular member 89

mounts the equalizer shaft 86 such that the teeth of the pinions 87 and 88 are enmeshed, respectively, with the racks 91 and 92 of the rods 62 and 63. A structurally sound arrangement results, in that a Z axis force on the walls of the slot 68 at a location closer to one of the rods 62 and 63 than to the other will not cause lateral flexure of the Z carriage assembly. Instead, the vertically mounted equalizer shaft 86 will, by virtue of the continuous engagement between the teeth of the pinions 87 and 88 and the teeth of the racks 91 and 92, maintain the rods 62 and 63 in vertical alignment. Thus, the wire guide support plate 61 will remain vertical at all times.

The X Carriage Drive or Distribution Mechanism

The X carriage 38 (FIGS. 1, 4 and 5) includes the bearing assemblies 64 and 66, which support the Z carriage 37, and the tubular member 89. A pair of rod-like members 101 and 102 project in parallel from the bearing members 64 and 66, respectively, extending rearwardly in the X direction. The rods 101 and 102 are supported for movement along the X axis by bearing members 103 and 104, 106 and 107, respectively.

A sleeve 108 surrounds a portion of the tubular member 89 intermediate the bearing assemblies 64 and 66. An X axis drive rod 109 extends rearwardly in the X direction from the sleeve 108, passing through a portion of the stationary frame 44 for support of the drive rod. Linear X axis movements of the drive rod 109 will result in like movements of the X carriage 38, which support the Z carriage 37. Thus, the wire guides 36 will be driven along the X axis.

The use of a sleeve member 108 to drive the tubular member 89 in the X direction will permit required vertical, Y axis movements of the X and Z carriages to occur. The position of driving contact between the sleeve 108 and the tubular member 89 will, however, vary with vertical displacement of the tubular member. Therefore, an equalizer shaft 111 (FIG. 5), mounting pinions 112 and 113 at its opposite ends, is utilized to maintain the structural integrity of the X carriage 38. The arrangement used is similar to that employed to avoid flexing of the Z carriage 37, as described previously. Thus, the equalizer shaft 111 is mounted to position the pinion 112 with its teeth engaging the teeth of a rack 114 on the rod 101 and the pinion 113 with its teeth engaging the teeth of a rack 116 on the rod 102.

The X axis drive motor 33 (FIGS. 4 and 7) is connected by means of the eddy current clutch 33A, the shaft 35, a belt 121 and two pulleys 122 and 123 to drive a main drive shaft 124. The main drive shaft 124 extends forwardly in the X direction to drive the spindles drive clutch 34. The main drive shaft 124 also is connected to drive a speed reducer 126. A tubular speed reducer output shaft 127 is mounted concentric with the main drive shaft 124 and extends back in a rearward X direction from the speed reducer 126. A pair of alternately engageable clutches 128 and 129 (see also FIG. 14E) are mounted along the speed reducer output shaft 127. A bevel gear 131 is mounted projecting rearwardly in the X direction on an output shaft 132 of the clutch 128. Another bevel gear 133 is mounted projecting forwardly in the X direction on an output shaft 134 of the clutch 129.

A bevel gear 136 is mounted on a shaft 137. The shaft 137 extends perpendicularly to the speed reducer

output shaft 127 and positions the bevel gear 136 with its teeth enmeshed both with the teeth of the bevel gear 131 and with the teeth of the bevel gear 133. The bevel gear 136 will be rotated in a clockwise direction, as seen in FIG. 7 looking along the shaft 137, with rotation of the shaft 127 in the direction of arrow 138, when the clutch 128 is engaged to drive the bevel gear 131. On the other hand, the bevel gear 136 will be rotated in a counterclockwise direction with rotation of the shaft in the direction of the arrow 138, when the clutch 129 is engaged to drive the bevel gear 133. The clutches 128 and 129 are to be engaged alternately so as to cause the bevel gear 136 and the shaft 137 to oscillate about the axis of the shaft 137, as illustrated by arrow 139. Meanwhile, the bevel gear 131 or 133 having its clutch 128 or 129 disengaged at any particular instant will be driven in idling condition by the bevel gear 136.

A worm 141 is mounted extending along the oscillatory shaft 137. The worm 141 has teeth maintained continuously in mesh with the teeth of a worm gear 142 mounted to a vertical shaft 143. The vertical shaft 143 is adapted to drive a sprocket wheel 144 (FIG. 6) when a distribution clutch 145 (see also FIG. 14E) is engaged. The sprocket wheel 144 and an idler sprocket wheel 146 are enveloped by a chain 147. Thus, rotary movements of the sprocket wheel 144 will impart peripheral movements to the chain 147 about the sprocket wheels 144 and 146.

A support bracket 148 is mounted for X direction movement along a rod 149 which is fixed to the stationary frame of the apparatus. The support bracket 148 is attached to the chain 147 to be driven along the rod 149 in the X direction upon movement of the chain. The arrangement is such that, when the distribution control clutch 145 is engaged to connect the shaft 143 to drive the sprocket wheel 144, oscillation of the shaft 137 (FIG. 7), as shown by the arrow 139, will cause reciprocation of the mounting bracket 148 (FIG. 6) in the X direction, axially along the rod 149.

A rod or lever 152 hangs downwardly from a pivot pin 153 carried by the mounting bracket 148. The lever 152 extends axially through a pair of sleeve members 154 and 156. The sleeve 154 is mounted on a pin 157 which is pivotally supported by a bracket 158 forming a part of the winding pitch adjusting mechanism 47. The sleeve 156 is mounted on a pin 159 which is pivotally supported by a hollow tubular member 161. The tubular member 161 is mounted for movement along the X direction only. The bracket 158 is fixed against all X direction movement. The arrangement is such that reciprocatory movement of the mounting bracket 148 (FIGS. 4 and 6) along the rod 149 will oscillate the lever 152 about the axis of the pivot pin 157, causing X direction reciprocatory movement of the tubular member 161 as shown by arrow 160 (FIG. 6). This motion of the tubular member 161 will be accompanied by limited axial movements of the oscillating rod or lever 152 relative to the sleeves 154 and 156 and by pivotal movements of the sleeves 154 and 156 about their respective pivot pin axes.

A crank mechanism 162 (FIGS. 4 and 5), including an eccentric portion 163, is mounted at a leading end of the tubular member 161. The eccentric 163 extends outwardly from the tubular member 161 along the Z

direction and passes through a vertical slot 164 formed in an enlarged trailing end portion 166 of the X axis drive rod 109. The crank mechanism 162 is mounted to a helical gear 167 which is connected to be rotated by another helical gear 168 of like diameter. The helical gear 168 is connected through a splined coupling member 169 to a shaft 171. The shaft 171 extends along the X direction within an axial bore of the tubular member 161. The crank mechanism 162 is mounted to be driven horizontally in the X direction by X direction movement of the tubular member 161. The splined coupling member 169 will meanwhile cause the crank mechanism 162 to be driven by the shaft 171 when the shaft 171 is rotated in any X position of the tubular member 161.

The crank mechanism 162 and the crank rotating members 167, 168, 169, 171 form part of a Z axis orbiting drive mechanism 170. The crank mechanism 162 also forms a part of a drive mechanism for displacing the X carriage 38 along the X direction. Briefly outlining the basic arrangement for reciprocating the X carriage 38 along the X axis as described above, the motor 33 (FIGS. 4 and 7) is connected to rotate the speed reducer output shaft 127 in the direction of the arrow 138. The alternated engagement of the clutches 128 and 129 with the shaft 127 will cause the bevel gear 136 and the shaft 137 to oscillate, as shown by the arrow 139. The resultant oscillation of the worm gear 141 will drive the chain 147 (FIGS. 4 and 6) and the support bracket 148 back and forth in the X direction through the sprocket wheel 144 to the shaft 143. The lever 152 is connected to be oscillated about the axis of the pivot pin 157 by X direction reciprocation of the support bracket 148. Such oscillation of the lever 152 will reciprocate the tubular member 161 in the X direction through the pivot pin 159. The X axis reciprocation of the tubular member 161 will be converted into X axis reciprocation of the X carriage 38 (arrow 160 in FIG. 6) through the crank mechanism 162 (FIGS. 4 and 5), the X axis drive rod 109 and the sleeve 108, the crank mechanism 162 being locked against rotation at this time. Thus, the X carriage 38 will be reciprocated, with the rods 101 and 102 moving axially of the bearings 103, 104, 106, 107 and the equalizer rod 111 maintaining the X carriage continuously in a non-flexed condition.

A mechanism for reversing the direction of X axis movement, by disengaging one of the clutches 128 or 129 while engaging the other clutch, in alternation, is shown in FIG. 5. An arm 176 is mounted extending downwardly from the tubular member 161. A member 177 projects rearwardly in the X direction from the arm 176 and extends to a clutch reversal signaling assembly 178. The clutch reversal signaling assembly may be formed by a pair of conventional limit switches and associated circuitry. Preferably, however, the clutch reversal signaling assembly 178 includes a conventional, adjustable, linear variable differential transformer of LVDT 179 (see also FIG. 14G) of which the member 177 constitutes an armature. Associated with the LVDT 179 are potentiometers 175 and 180 (FIG. 14G) which may be adjusted to provide reversal signals to the clutches 128 and 129 at desired limit positions for X direction movement of the armature 177. Thus, end points may be established for X axis movements of

the wire guides 36, which movements are to be provided by the various elements of the X carriage drive mechanism including the tubular member 161, displacing the arm 176 and the reversal-signaling armature 177.

The X Axis Winding Pitch Adjusting Mechanism

The winding pitch adjusting mechanism 47 (FIG. 6) includes several elements which also form part of the X carriage drive mechanism. The common elements are the lever 152, the pivot pin 153, the sleeves 154 and 156, the pivot 157, the bracket 158 and the pivot pin 159.

The bracket 158 is supported for Y direction movement along the stationary frame 44 of the apparatus. A threaded shaft 181 extends axially along the Y direction and passes through an internally threaded opening 182 through the bracket 158. The threaded portions of the shaft 181 and the opening 182 are mated such that rotation of the threaded shaft 181 will drive the bracket 158 axially along the shaft 181. The arrangement provided for mounting the bracket 158 on the frame 44 constrains the bracket against all movement other than in the Y direction.

The winding pitch adjusting motor 48 is connected through a shaft 186 to drive a bevel gear 187. The teeth of the bevel gear 187 are maintained enmeshed with the teeth of another bevel gear 188 which is mounted on the vertical threaded shaft 181. Thus, rotation of the motor 48 will cause the threaded shaft to rotate. Such rotation of the threaded shaft 181 will drive the bracket 158, and with it the pivot pin 157 and the sleeve 154, upwardly or downwardly (arrow 189) along the shaft 181 depending upon the direction of the rotation.

As discussed above, the X axis drive arrangement for the X carriage 38 includes the lever 152. Oscillatory motion of the lever 152 about the axis of the pivot pin 157 will translate X direction reciprocation of the support bracket 148 into X direction reciprocation of the tubular member 161 and, thus, of the X carriage 38. The rate of reciprocation of the support bracket 148 will be in fixed ratio to the speed of rotation of the pulley 122 (FIGS. 4 and 7) and, thus, of the spindles 31. However, the driving effect upon the tubular member 161 and the X carriage 38 of the fixed speed movements of the support bracket 148 will depend upon the relative vertical lengths of the lever arms 152A and 152B (FIG. 6) of the lever 152. The winding pitch adjusting motor 48 may be operated to displace the bracket 158 axially of the threaded shaft 181 so as to alter the vertical position of the pivot pin 157 with respect both to the vertically-fixed rod 149, which carries the support bracket 148, and to the vertically-fixed tubular member 161. In this manner, relative vertical lengths of the lever arms 152A and 152B may be varied.

Accordingly, a desired rate may be selected for X direction movement of the tubular member 161 and the X carriage 38. The winding pitch adjusting motor 48 may be operated, as directed by the control system, to position the bracket 158 at an appropriate Y location on the threaded shaft 181. Displacement of the support bracket 148 at fixed speed along the rod 149 will thereafter displace the X carriage 38 along the X axis at the selected rate of movement. Reversals in the direction of movement of both the support bracket 148

and the X carriage 38 will, meanwhile, result from alternated engagement of the clutches 128 and 129 (FIG. 7), in response to signals provided by the clutch reversal signaling assembly 178 (FIG. 5) at desired limit points for X carriage travel.

An LVDT 191 (FIGS. 6 and 14G), similar to that used in the clutch reversal signaling mechanism 178, may be utilized to detect the axial position of the bracket 158 on the threaded shaft 181. An upper end (not shown) of the shaft 181 is threaded at a much finer pitch than the portion of the shaft 181 which passes through the threaded opening 182 in the bracket 158. Rotation of the shaft 181 will cause an armature (not shown) of the LVDT 191 to be driven axially of the shaft through engagement between threads on the armature and the threads at the upper end of the shaft. A projecting finger 192 extends from the LVDT armature through a vertical slot 193 in the casing of the LVDT 191 in order to prevent any rotary movement of the armature. The position of the armature may be sensed to provide an indication of the axial location of the bracket 158 on the threaded shaft 181.

The X Axis Rapid Traverse Mechanism

The X axis rapid traverse mechanism 46 (FIGS. 4, 6 and 7) includes several elements which also form part of the X carriage drive or "distribution" mechanism. The common elements are the motor 33 (FIGS. 4 and 7), the oscillatory shaft 137, the various elements of the drive train connected between the motor 33 and the shaft 137, the tubular member 161, the crank mechanism 162 (FIGS. 4 and 5), the X axis drive rod 109 and the sleeve 108.

The oscillatory shaft 137 (FIGS. 4 and 7) is connected at an end remote from the bevel gear 136 to a rapid traverse clutch 201 (see also FIG. 14E). The rapid traverse clutch 201 will be engaged to drive the rapid traverse mechanism 46 only during such time as the distribution clutch 145 (FIGS. 4, 6 and 14E) of the X carriage drive mechanism and the forward-driving clutch 129 (FIG. 7) are disengaged, with the rearward-driving clutch 128 engaged. Therefore, only one of the X carriage drive and rapid traverse mechanisms will be connected at any instant to drive the elements common to both mechanisms. A distribution brake 202 (see also FIG. 14E) will be engaged to stop rapidly X axis motion of the X carriage 38 so as to place the X carriage in approximate location for a final position-fixing operation of an X carriage detenting assembly 205 (FIG. 12).

A crank shaft 203 (FIGS. 4 and 7) and a crank arm 204 are connected to be driven by the oscillatory shaft 137 when the rapid traverse clutch 201 is engaged and the distribution brake 202 is disengaged. A drive rod 206 extends forwardly generally in the X direction from the crank arm 204. The drive rod 206 is connected to the tubular member 161 (FIGS. 4 and 6) at a position approximately midway of the tubular member. The arrangement is such that, with the rapid traverse clutch 201 engaged and the distribution clutch 145 disengaged, a counterclockwise angular displacement of the crank shaft 203 (FIGS. 4 and 7) will provide a rearward linear displacement of the drive rod 206 (arrow 207 in FIG. 7) and the tubular member 161 to move the X carriage 38 in the rearward X direction. On the other hand, with the rapid traverse clutch 201 disengaged and the distribution clutch 145 engaged, linear

displacement of the drive rod 206 caused by the lever 152 (FIG. 6) will provide angular displacement of the crank shaft 203 in an idling condition of the crank shaft.

5 The rate of movement of the X carriage in the X direction provided by the rapid traverse mechanism 46 will be much greater than that provided by the principal X carriage drive mechanism which includes the lever 152 (FIGS. 4 and 6). The disparity in the rates of movement is due to the differences in geometry of the two mechanisms.

The Y Carriage Drive Mechanism

Referring to FIGS. 4 and 5, the Y carriage 39 includes the bearing members 103, 104, 106, and 107, which support the X carriage rods 101 and 102. A vertical column 211 interconnects the bearing members 103 and 106. Another vertical column 212 interconnects the bearing members 104 and 107. The column 211 is mounted for vertical movement in two sleeve bearings 213 and 214 which are fixed to the stationary frame 44 of the apparatus. The column 212 is mounted for vertical movement in two sleeve bearings 216 and 217 which are also fixed to the frame 44.

A three-sided bracket member 221 is mounted to the columns 211 and 212, bridging the space between the columns. The bracket member 221 carries a cam follower 222 which supports the bracket member by engagement with a spiral-shaped camming groove 223 in a Y level cam 224. The cam 224 is mounted to a cam shaft 226 which passes through a bearing in a vertical plate 227. The plate 227 will be maintained fixed against vertical movement except during operation of the Z axis orbital drive mechanism. The columns 211 and 212, as well as the three-sided bracket member 221, are mounted for vertical, Y direction movement with respect to the plate 227 upon rotation of the cam 224. No other relative movement between the columns 211 and 212 and the bracket member 221, on the one hand, and the plate 227, on the other, is permitted by the mounting arrangement.

The Y axis drive motor 41 (FIGS. 4 and 10) has an output shaft 231 connected to a drive pinion 232. The drive pinion 232 has its teeth engaged with the teeth of a gear 233 mounted to rotate a Y axis drive shaft 234. The Y axis drive shaft 234 is connected through a flexible coupling 236 (FIGS. 4 and 5) to rotate the cam shaft 226. Operation of motor 41 will, thus, rotate the

50 Y level cam 224. The follower 222 will be cammed vertically, radially of the rotating cam, by the spiral camming groove 223. As a result, the three-sided bracket member 221 and the columns 211 and 212 will be displaced vertically within the bearing members 213, 214, 216 and 217. In turn, the X and Z carriages 38 and 37, respectively, will be lifted or lowered, changing the level of the wire guides 36 along the Y axis.

Another LVDT 237 (FIGS. 4, 10 and 14G), having 60 an armature 238 which terminates in a rack 239, is utilized to sense the vertical position of the Y carriage 39. The position of the Y axis drive shaft 234 dictates the position of the rack 239 through a drive train consisting of a pinion 241 mounted to the Y axis drive shaft 234, a relatively large diameter gear sector 242 having teeth engaged with the teeth of the pinion 241, and a relatively small diameter gear sector 243 integral with the

gear sector 242 and having teeth engaged with the teeth of the rack 239. A spring 244 is connected between the armature 238 and the frame 44 in order to eliminate all gear backlash, thereby insuring repeatable accuracy in output signals from the LVDT 237.

The Z Axis Orbital Drive Mechanism

The Z axis orbital drive mechanism includes several elements which also form part of the X carriage drive mechanism and several elements which also form part of the Y carriage drive mechanism. More specifically, the Z axis orbital drive mechanism includes all elements of the X carriage drive mechanism which are to be driven by reciprocation of the tubular member 161 and all elements of the Y carriage mechanism which are to be driven by rotation of the cam shaft 226. All of these elements are adapted to be driven simultaneously, through operation of the Z axis orbital drive motor 43 (FIGS. 4 and 7). The Z axis orbital drive mechanism will function to drive these common elements in such manner as to impart X and Y harmonic component movements of equal magnitudes to the X and Y carriages 38 and 39, respectively, in timed relationship. The resultant pattern of motion will provide orbital movement of the wire guides 36 about the Z axis.

The Z axis orbital drive motor 43 (FIGS. 4 and 7) is connected to rotate a sprocket 251 which is, in turn, connected by means of a chain 252 to rotate another sprocket 253. The sprocket 253 is mounted to the shaft 171 which passes axially through the hollow tubular member 161 and which is connected through the splined coupling 169 (FIG. 5) to rotate the crank mechanism 162.

A slot 256 (FIGS. 4 and 5), elongated horizontally in the X direction, extends through a lower portion of the vertical plate 227. The slot 256 is located adjacent to the vertical slot 164 in the enlarged trailing end portion 166 of the X axis drive rod 109. The eccentric portion 163 of the crank mechanism 162 extends along the forward Z direction perpendicularly through both the vertical, Y direction slot 164 and the horizontal, X direction slot 256. The slots 164 and 256 are each of sufficient length to house the eccentric portion 163 during complete rotation of the crank mechanism 162. The crank mechanism is of sufficient rigidity to support on the eccentric 163 the weight of the Y carriage 39, the X carriage 38, the Z carriage 37 and several of the Y carriage drive elements.

Rotation of the eccentric 163 about the axis of the crank mechanism 162 will provide harmonic X and Y component movements of an overall orbital motion to the X and Y carriages. A cyclically varying, harmonic X component will be applied from the rotating eccentric 163 to the tubular member 89 of the X carriage 38 through the X axis drive rod 109 and the sleeve 108. A cyclically varying, harmonic Y component of like magnitude will be applied from the rotating eccentric 163 to the columns 211 and 212 of the Y carriage 39 through the plate 227. The cam shaft 226, the cam 224, the follower 222 and the three-sided bracket 221. The resultant effect of the harmonic component motions will be an orbital motion of the wire guides 36 about the Z axis at a desired radius, equal to the eccentricity of the eccentric 163. The flexible coupling 236 between the cam shaft 226 and the Y carriage drive

shaft 234 will permit the limited Y direction displacement of the vertical plate 227 required for Z axis orbital motion.

5 A pair of switches 261 and 262 (FIGS. 4 and 7) are utilized to sense the number of rotations and the angular orientation of the shaft 171 and, thus, of the crank mechanism 162. Two cam followers 263 and 264 are connected to actuate the switches 261 and 262, respectively, when contacted by the raised lobe 266 of a cam 10 267. A pair of enmeshed gears 268 and 269 connect the shaft 171 to rotate a cam shaft 271 to which the cam 267 is mounted.

The Spindles Drive Mechanism

The motor 33 (FIG. 4) is connected to operate the spindles drive clutch 34, as has been discussed above, through the belt 121, the pulleys 122 and 123 and the main drive shaft 124. An output shaft 276 (FIGS. 8 and 9) of the spindles drive clutch 34 mounts a bevel gear 277. The teeth of the bevel gear 277 are enmeshed with the teeth of a master bevel gear 278 on a vertical spindles drive shaft 279. Four other bevel gears 278 are spaced at equal distance along the vertical spindles drive shaft 279. Each of the five bevel gears 278 has its teeth enmeshed with those of a different spindle gear 281. The spindle gears 281 are each mounted to a different one of the spindles 31. The arrangement is such that rotation of the spindles clutch output shaft 276 will result in rotation of the five spindles 31.

30 A conventional pickup 282 for an electronic rotations counter 280 (FIG. 14G) and a lubricant pump 283 are shown in FIG. 8 as being driven from opposite ends of the spindles drive shaft 279. A spindles brake 284 (see also FIG. 14E) and a detent disc 286 are also 35 associated with the spindles drive shaft 279. The spindles brake 284 will function to stop the rotation of the shaft 279 and, thus, of the spindles 31 substantially simultaneously with disengagement of the spindles drive clutch 34. Such braking operation will take place 40 when the number of wire winding or tape applying rotations of the spindles 31, as determined by the counter 280, corresponds to that desired for the particular coil being wound or taped, as determined by the programmable device 56 (FIG. 1). The detent disc 286, which has two diametrically opposed notches 287 and 288 in its periphery, will cooperate with a detent 45 plunger 289 to assure that the spindles 31 are stopped by the brake 284 in proper angular position for subsequent wire wrapping operations on the bobbins 21 carried by the spindles.

An air cylinder 291 is utilized to position the detent plunger 289 either in locking engagement (FIG. 9) with one of the detent disc notches 287 and 288 or in a 50 withdrawn position (FIG. 8), spaced from the periphery of the detent disc 286. A camming bar 292, a pair of followers 293 and 294, and a pair of switches 296 and 297 are arranged as shown in FIGS. 8 and 9 and in FIG. 14B to sense the position of the detent 55 plunger 289.

The Taping Carriage Drive Mechanism

The taping carriage 51 (FIGS. 1, 8, 9 and 13A through 13D) constitutes a large, vertically extending plate member which is mounted to move in the Z direction on two fixed support rods 301 and 302. A pair of racks 303 and 304 (FIG. 8) are mounted to the taping carriage 51 and extend along the Z direction. A ver-

tical output shaft 306 projects axially from opposite ends of the vertically mounted taping carriage motor 52 and carries two drive pinions 307 and 308. The teeth of the pinions 307 and 308 are enmeshed with the teeth of the racks 303 and 304, respectively. Thus, rotary motion of the taping carriage motor output shaft 306 will drive the taping carriage 51 linearly along the Z axis on the support rods 301 and 302.

Five reels 311 (FIGS. 1 and 13A through 13D) of the tape 26 are mounted on the taping carriage 51. Each of the reels 311 carries tape to be applied to a different one of the five bobbins 21 which are mounted on the five spindles 31. Only the bottommost reel 311 is shown in FIGS. 13A through 13D.

A number of tape guiding and tensioning rollers 312, 313 are mounted on the taping carriage. The rollers 312 and 313 guide the tape 26 from each reel 311 into contact with the periphery of an associated tape applying wheel 314. Five such wheels 314 are mounted along a rearward edge 315 of the taping carriage 51 on five stub shafts 316. The tape applying wheels project rearwardly over the rearward edge 315 toward the spindles 31. The tape applying wheels 314 are preferably composed of an elastomeric material, such as rubber.

The stub shafts 316 are carried by five wheel mounting blocks 317. Each wheel mounting block 317 is pivotally supported by a different pin 318 located along the rearward edge 315 of the taping carriage 51. Springs 319 are mounted in suitable positions to bias the wheel mounting blocks 317 normally pivoted rearwardly about the pins 318 into contact with associated stops 321. Five stops 321 are positioned rearwardly in the Z direction from the rearward edge 315 of the taping carriage 51 with each stop located to the rear of a different wheel mounting block.

A radial arm 326 is mounted on each stub shaft 316 and is adapted to be pivoted about the stub shaft upon energization of a solenoid 327 (see also FIG. 14F). Each radial arm 326 is of larger radius than the associated tape applying wheel 314 and mounts a knife-edged tape cutter 328 and a brush 329 adjacent to a radially outward end of the arm.

A taping carriage locator assembly 330 (FIGS. 1 and 8), including four switches 331, 332, 333 and 334 (FIGS. 13A through 13D and 14C), is mounted to the stationary frame 44 of the apparatus beneath the taping carriage 51. A camming bar assembly 336 (FIGS. 13A through 13D) is mounted to the bottom of the taping carriage. Various camming surfaces of the camming bar assembly 336 are positioned in Z direction alignment with the switches 331, 332, 333 and 334, respectively. These camming surfaces will actuate one or another of the four switches in four selected positions of the taping carriage 51.

Other Mechanisms of the Coil Winding Apparatus

A notched cutter rod 351 (FIGS. 1 and 13A through 13D) and an anchor pin 352 are associated with each of the five spindles 31. The cutter rods and anchor pins are located adjacent to the taping carriage 51 and extend in parallel along the Z direction toward the wire guides 36. Pairs of parallel apertures in five bearing blocks 353 each house portions of one of the cutter rods 351 and one of the anchor pins 352. Five air cylinders 354 may be actuated to provide short-displacement, Z axis movements to the five cutter rods 351,

under the control of a pair of solenoid valves 350 and 355 (FIG. 14C). Five anchor pin pusher blocks 356, carried by the taping carriage 51, may be utilized to displace the five anchor pins 352 in the forward Z direction by pressure against anchor pin heads 357 to overcome the bias of five associated springs 358. Movement of each cutter rod 351 in the forward Z direction through its respective aperture in a bearing block 353 will sever a segment of the wire 23 (FIG. 13C) between the notch in the cutter rod and a close-fitting, sharp edge of the aperture. Movement of each anchor pin 352 in the forward Z direction through its respective aperture in a bearing block 353 will strip from the anchor pin (FIG. 13B) several turns of wire 23, which turns will have previously been wrapped about the anchor pin (FIG. 13C) by Z axis orbital movements of the associated wire guide 36.

Referring next to FIGS. 4 and 12, the detenting assembly 205 includes a detent plate 361 which is mounted extending transversely from the tubular member 161 of the X carriage drive mechanism. A pair of detent notches 362 and 363 are provided in the plate 361 for locking the tubular member 161 fixed in either of two wire wrapping positions. In a first wire wrapping position, a first detent 364 occupies the notch 362. This locates the wire guides 36 in appropriate X axis positions such that rotation of the crank mechanism 162 will orbit the wire guides each about a selected bobbin terminal 27. In a second wire wrapping position, as depicted in FIG. 12, a second detent 366 occupies the notch 363. This locates the wire guides 36 in appropriate X axis positions such that rotation of the crank mechanism 162 will orbit the wire guides each about a different anchor pin 352. Air cylinders 367 and 368 may be actuated to displace the detents 364 and 366, respectively, between fully extended, locking positions and withdrawn, rest positions. With one of the detents withdrawn from its notch, the other detent may be advanced toward its own notch. The spring between the first and second wire wrapping positions of the tubular member 161 is relatively slight. Thus, the advancing detent will be forced into its own notch from a slightly off-set position. The advancing detent will cam the detent plate 361 from one of the two wire wrapping positions of the tubular member into the other. Several switches 371, and 372, 373 and 374 may be arranged to sense the position of the detents 364 and 366, respectively, in the manner illustrated in FIGS. 12 and 14B.

Turning now to FIGS. 4 and 5, a wire guide Y level adjusting mechanism 381 is adapted to raise or lower the wire guide support plate 61 with respect to the vertical wire guide mounting bar 60. This mechanism may be utilized when it is desired to wind coils on bobbins differing from that shown in FIG. 3. For example, substitute bobbins might provide twelve terminals 27 in order to produce transformers having six windings each. A slight Y level adjustment may be required to align the wire guides 36 with the substitute bobbins. The necessary readjustment may occur through the manipulation of an eccentric shaft 382. The eccentric shaft 382 supports the base of the wire guide support plate 61 in a mounting bracket 383 at the base of the wire guide mounting bar 60. Manual or solenoid-induced rotation of the eccentric shaft 382 between spring detented positions along the periphery of the

shaft will raise or lower the wire guide support plate 61 with respect to the mounting bracket 383. The eccentric shaft 382 may be rotated through 180° between highest and lowest positions of the wire guides 36, the displacement corresponding to the throw of the eccentric. A sensing system for determining the position of the eccentric shaft 382 is provided (FIG. 5) by switches 386 and 387, actuatable by reference surfaces 388 and 389 formed on the eccentric shaft 382.

The Control System

An appropriate control circuit for use with the winding apparatus of FIGS. 1 through 13D is depicted in FIGS. 14A through 14G and 16. The control circuit includes the sequencing device 57 (FIG. 14A) and a number of switches 5701A, 5701B, 5702, 5703, etc., (FIGS. 14A through 14G) actuated between different conditions of operation at selected times by the sequencing device 57.

The sequencing device 57 may be a rotary drum of a type which includes a number of pegs, inserted into apertures suitably disposed about a cylindrical surface, for actuating the switches 5701A, 5701B, 5702, 5703, etc., in an appropriate time sequence during each rotation of the drum. A suitable arrangement of the pegs is demonstrated by the timing chart of FIGS. 15A and 15B. The switch-actuating drum 57 will provide overall control of each multiple winding and multiple taping cycle of the apparatus, subject to conditions specified by any selected program card utilized with the program-controllable device 56. The use of removable pegs, inserted into appropriate ones of a multiplicity of apertures disposed in suitable positions along the cylindrical surface of the drum 57, will permit simple adjustability of switching operations not possible through the alternative use of fixed camming surfaces on a rotary, switch actuating device.

A drum motor (not shown) is included in the switch-actuating drum mechanism 57 to provide stepped rotation of the drum 57. The internal circuitry of the drum 57 will cause a short dwell after each indexing operation of the drum motor such that various relays may respond to changed conditions of the overall control circuit effected by each new closing or opening of the drum-controlled switches 5701A, 5701B, 5702, 5703, etc. An open condition of any one of several interlock contacts 423C, 426A, 442A, 443A, . . . 416B, (bottom of FIG. 14A) will ordinarily cause the drum to remain stationary until further changes in conditions of the overall control circuit cause contact reclosing. At certain times during each cycle, however, one or more of the drum-controlled switches may be closed to bypass various interlock contacts and, thus, override the function of the interlock contacts. Such overriding operation will occur whenever necessary to provide a correct, continuing sequence of operations.

An initial condition of the various switches controlled by the rotary, switch actuating drum 57 is that shown in the circuit diagram of FIGS. 14A-14G. All of the drum-controlled switches, other than those indicated in the top horizontal line of the timing chart (FIG. 15A), are shown in the normal conditions of the switches, i.e., the conditions toward which the switches are biased. The drum-controlled switches indicated in line one of the timing chart are initially held in an actuated condition by pegs on the drum 57, as illustrated in

the circuit diagram. Thus, initially held closed, or in a second condition, are the normally open, or normally first condition, switches 5701A, (FIG. 14A), 5706 (FIG. 14B), 5708 (FIG. 14B), 5713 (FIG. 14E) and 5732 (FIG. 14D), and initially held in an open condition are the normally closed switches 5701B (FIG. 14A), and 5703 (FIG. 14A).

The apparatus control circuit of FIGS. 14A through 14G also includes a number of contacts 5601, 5602, etc. of the program controllable device 56 (FIG. 1). These contacts 5601, 5602, etc., may be of a type wherein a number of contact pairs are spring-biased together to provide a continuous electrical path through appropriately positioned holes in a program card, while not providing a continuous electrical path at positions in which such card does not have holes.

A power source 401 (FIG. 14A) provides power for the control circuit through a main switch 402. A "-main" relay 403 includes normally open contacts 403A, 403B, and 403C in lines for providing power to the main drive motor 33, as well as a normally open holding contact 403D and an additional normally open contact 403E (all in FIG. 14A). Energization of the main relay 403 to operate the main drive motor initially takes place upon the manual closing of a normally open "On" switch 404 by way of a transformer 406, a normally closed "Off" switch 407, and one of a pair of parallel lines 408, 409. The line 408 includes a normally open contact 411A of a "ten terminals" relay 411 and a normally closed contact 412A of a "twelve terminals" relay 412, while the line 409 includes a normally closed contact 411B of the ten terminals relay 411 and a normally open contact 412B of the twelve terminals relay 412. The ten terminals relay 411 has three additional, normally open contacts 411C (FIG. 14C), 411D (FIG. 14E), and 411E (FIG. 14E), while the twelve terminals relay 412 also has three additional, normally open contacts 412C (FIG. 14C), 412D (FIG. 14E) and 412E (FIG. 14E). Closed contacts 5601 (FIG. 14A) and either 5602 or 5603 of the program-controllable device 56 will provide power to either the ten terminals relay 411 or the twelve terminals relay 412, depending upon the number of terminals of any particular type of bobbin which is to be wound by the apparatus. Thus, either contact 411A in line 408 or 412B in line 409 will be closed during the initial closing of the "On" switch 404.

A contact 5604 (FIG. 14A) of the program-controllable device 56 will be closed when it is desired to provide power to a "wire cut" relay 413 and to a "last wire cut" relay 414. The wire cut relay 413 has two normally closed contacts 413A and 413B (both in FIG. 14C) and one normally open contact 413C (also in FIG. 14C). The last wire cut relay 414 has two normally closed contacts 414A (FIG. 14B) and 414C (FIG. 14E) and two normally open contacts 414B (FIG. 14B) and 414D (FIG. 14E).

A "cycle control" relay 416 (FIG. 14A) will be energized through the closed contact 403E of the energized main relay 403 upon the manual closing of a normally open "Start Cycle" contact 417A of a "Cycle Control" switch 147. The path of energization of the relay 416 includes a normally closed "Stop Cycle" contact 417B of the switch 417, a "Run/Reset" switch 418 and a "-Cycle-Normal/End" switch 419 (FIGS. 14A and 14D).

The cycle control relay 416 has a normally open holding contact 416A (FIG. 14A) plus two additional normally open contacts 416B (FIG. 14A) and 416D (FIG. 14G) and one normally closed contact 416C (FIG. 14C). It is the initial closing of the normally open contact 416B (FIG. 14A), upon the closing of the "Cycle Control" switch 417 and the energizing of the cycle control relay 416, which will provide power for initiating operation of the sequencing device 57 to start the operative cycle of the coil winding apparatus.

A "last winding latch" relay 421 (FIG. 14A) includes a latching solenoid 421L and an unlatching solenoid 421UL. The last winding latch relay 421 will operate to close normally open contacts 421A (FIG. 14A), 421C (FIG. 14C) and 421D (FIG. 14D), as well as to open normally closed contacts 421B (FIG. 14A) and 421E (FIG. 14D), when the latching solenoid 421L is energized through the closing of a normally open contact 422B of a "last winding relay" 422 (FIG. 14D). The last winding latch relay 421 will operate to return its contacts to their normal, depicted conditions only upon energization of the unlatching solenoid 421UL through the closing of a "Drum Home" switch 5701A by the sequencing device 57, i.e., the rotating drum.

In addition to the normally open contact 422B, the last winding relay 422 has a normally closed contact 422A (FIG. 14A) in a line for providing power to the last wire cut relay 414 and two normally open contacts 422C (FIG. 14C) and 422D (FIG. 14D).

A "reset drum latch" relay 423 (FIG. 14A) includes a latching solenoid 423L and an unlatching solenoid 423UL. The reset drum latch relay will operate to open normally closed contacts 423A, 423C (both in FIG. 14A) and 423D (FIG. 14D), as well as to close normally open contact 423B (FIG. 14A), when the latching solenoid 423L is energized either through a line 424 upon a manual "Reset" operation of the "Run/Reset" switch 418 or through a line 425 which includes a "Reset Drum Controls" drum switch 5702. The reset drum latch relay 423 will operate to return its contacts to their normal, depicted conditions only upon energization of the unlatching solenoid 423UL through the "Drum Home" switch 5701A.

Two "spindles detent" relays 426 and 427 (both in FIG. 14B) are associated with a "Spindles Detents" drum switch 5704, the spindles detent plunger position sensing switches 296 and 297 (FIGS. 8 and 9), a "spindles detent out" solenoid valve 428 and a "spindles dent in" solenoid valve 429. The first spindles detent relay 426 has normally open contacts 426A (FIG. 14A), 426B (FIG. 14B), 426C (FIG. 14C), and 426D (FIG. 14D), while the second spindles detent relay 427 has normally open contacts 427A (FIG. 14B) and 427B (FIG. 14C). These contacts of the two spindles detent relays 426 and 427 will act as interlocks to control operations of various mechanism of the coil winding apparatus, dependent upon any current position of the spindles detent plunger 289 (FIGS. 8 and 9) as detected by the switches 296 and 297. The "Spindles Detents" drum switch 5704 (FIG. 14B) will govern the position of the spindles detent plunger 289 by energization of one or the other of the position-controlling solenoid valves 428 and 429, which are associated with the air cylinder 291 (FIGS. 8 and 9).

An "X terminal detent" relay 431, an "X anchor detent" relay 432 and an "X detents" relay 433 (all in FIG. 14B) perform for the X carriage detenting assembly 205 (FIG. 12) the same general function as is performed for the spindles detent plunger 289 (FIGS. 8 and 9) by the two spindles detent relays 426 and 427. Also associated with the X carriage detenting assembly 205 are an "X Anchor Detent Relay Interlock" drum switch 5706, an "X Terminal Detent" drum switch 5707, an "X Anchor Detent" drum switch 5708 (all in FIG. 14B), the switches 371 through 374 (also shown in FIG. 12), an "X terminal detent in" solenoid valve 436, an "X terminal detent out" solenoid valve 437, an "X anchor detent in" solenoid valve 438 and an "X anchor detent out" solenoid valve 439.

The X terminal detent relay 431 (FIG. 14B) has a normally open contact 431A (FIG. 14B). The X anchor detent relay 432 has normally open contacts 432A, 432B (both in FIG. 14B) and 432C (FIG. 14C), as well as normally closed contacts 432D (FIG. 14C) and 432E (FIG. 14D). The X detents relay 433 has normally open contacts 433A (FIG. 14A), 433B (FIG. 14B), 433C (FIG. 14C) and 433D (FIG. 14D).

25 A "Y check relay" 441 (FIG. 14B) has normally open contacts 441A (FIG. 14A) and 441B (FIG. 14C) and a normally closed contact 441C (FIG. 14C).

A Z relay 442 (FIG. 14B) has normally open contacts 442A (FIG. 14A), 442B (FIG. 14B), 442C (FIG. 14C) and 442D (FIG. 14D). The Z relay contacts provide interlocks associated with the operation of the Z carriage drive motor 42 (FIGS. 11 and 14B).

A "wire guide" relay 443 (FIG. 14C) has normally open contacts 443A (FIG. 14A) 443B (FIG. 14B), 443C (FIG. 14C), 443E (FIG. 14C) and 443F (FIG. 14D), as well as a normally closed contact 443D (FIG. 14C). The wire guide relay 443 and its contacts are associated with the Z axis orbital motor 43 (FIGS. 7 and 14C), as are the limit switches 261, 262 (both in FIGS. 7 and 14C) and 386, 387 (both in FIGS. 5 and 14C). The limit switches 261 and 262 are positioned to sense opposite orientations of the wire guides 36 to direct wire wrapping operations on the terminals 27 (FIG. 2) or the anchor pins 352 (FIGS. 13A-13D). The limit switches 386 and 387 are positioned to sense whether the Y level adjusting mechanism 381 (FIG. 5) is set for bobbins 21 of a configuration having ten or twelve terminals.

50 A "wire guide latch" relay 451 (FIG. 14C) includes a latching solenoid 451L and an unlatching solenoid 451UL. Energization of the latching solenoid 451L when a "Wire Guide Latch" drum switch 5709 is closed will open normally closed contacts 451A (FIG. 14A) and 451C (FIG. 14C) and close a normally open contact 451B (FIG. 14C). Only a subsequent energization of the unlatching solenoid 451UL through a "Terminal Wrap" drum switch 5722, an "Anchor Pin Wrap" drum switch 5723B and the relay contact 443D

55 will return the contacts of the wire guide latch relay 451 to their normal, depicted conditions.

60 A "tape latch" relay 452 (FIG. 14C) includes a latching solenoid 452L and an unlatching solenoid 452UL. Energization of the latching solenoid 452L through operation of the switch 331 (see also FIGS. 13A through 13D) will open normally closed contacts 452A and 452C and close a normally open contact

65

452B (all in FIG. 14C). Only a subsequent energization of the unlatching solenoid 452UL through operation of the switch 334 (see also FIGS. 13A through 13D) will return the contacts of the tape latch relay 452 to their normal, depicted conditions.

An "apply tape" relay 453 and an "apply tape time delay" relay 454 (both in FIG. 14C) are coupled in parallel both to be energized upon closing of a "Start Tape" drum switch 5726B. The apply tape relay 453 has normally open contacts 453A, 453B (both in FIG. 14C), 453D (FIG. 14E), 453F and 453G (both in FIG. 16), as well as normally closed contacts 453C (FIG. 14C) and 453E (FIG. 14E). The apply tape time delay relay 454 functions, upon energization and subsequent to the operation of the contacts of the apply tape relay 453, to close a normally open contacts 454A (FIG. 14C).

A "tape wrap" relay 456 (FIG. 14C) is connected to be energized upon a momentary closing of the switch 332 while the taping carriage 51 is moving from the position of FIG. 13C to that of FIG. 13D. The tape wrap relay has normally closed contacts 456A and 456D and normally open contacts 456B and 456C (all in FIG. 14C).

A "mid-stroke" relay 457 (FIG. 14C) is connected to be energized upon a closing of the contact 456C. The mid-stroke relay has normally open contacts 457A (FIG. 14A), 457D and 457E (both in FIG. 14C) and normally closed contacts 457B (FIG. 14A) and 457C (FIG. 14C).

A pair of "auxiliary X anchor detent" relays 458 and 459 (both in FIG. 14C) are coupled to be energized from a d.c. power source 461 when the contacts 432C or 432D, respectively, of the X anchor detent relay 432 (FIG. 14B) are closed. The first auxiliary X anchor detent relay 458 has normally open contacts 458A, 458B and 458C (all in FIG. 14G), while the second auxiliary X anchor detent relay 459 has normally open contacts 459A, 459B and 459C (also all in FIG. 14G).

A "distribution control" relay 462 (FIG. 14D) is coupled to be energized when a "Start Wind" drum switch 5720 is closed. The distribution control relay has normally open contacts 462A (FIG. 14A), 462B, (FIG. 14C), 462D (FIG. 14D), and 462E (FIG. 14E), as well as normally closed contacts 462C (FIG. 14C) and 462F (FIG. 14E).

An "X extend" relay 463 (FIG. 14D) is also coupled to be energized when the "Start Wind" drum switch 5720 is closed. The X extend relay 463 has a normally open holding contact 463A, another normally open contact 463B (FIG. 14E) and a normally closed contact 463C (FIG. 14E).

A "fast wind" relay 464 (FIG. 14D) will be normally energized through the closed "Start Wind" drum switch 5720 as long as a "Slow Wind" contact 280A of the electronic counter 280 (FIG. 14G) remains in its illustrated, normally closed (FIG. 14D) position, i.e., prior to the winding of a predetermined number of turns of wire 23 about each bobbin 21 such that only a few more turns are to be wound. The fast wind relay 464 has normally open contacts 464A and 464B and normally closed contacts 464C and 464D (all in FIG. 16) associated with a conventional, adjustable speed drive control circuit 465 of the X axis distribution motor 33, its eddy current clutch 33A and its eddy current brake 33B.

A "wind" relay 466 (FIG. 14D) is also coupled to be energized when the "Start Wind" drum switch 5720 is closed. The wind relay has normally closed contacts 466A (FIG. 14C) and 466D (FIG. 14E), as well as normally open contacts 466B (FIG. 14D) and 466C (FIG. 14E).

A "wind X motion" relay 467 (FIG. 14D) is also coupled to be energized when the "Start Wind" drum switch 5720 is closed. The wind X motion relay has normally open contacts 467A (FIG. 14D), 467B, and 467D (both in FIG. 14E), as well as a normally closed contact 467C (FIG. 14E).

A "spindles winding and X motion" relay 468 (FIG. 14D) is also coupled to be energized when the "Start Wind" drum switch 5720 is closed. The spindles wind and X motion relay has normally open contacts 468A (FIG. 14A), 468C (FIG. 14D), 468D and 468E (FIG. 16), and a normally closed contact 468B (FIG. 14A).

A "first winding" relay 471, a "second winding" relay 472, a "third winding" relay 473, a "fourth winding" relay 474, a "fifth winding" relay 475 and a "sixth winding" relay 476 are all depicted in FIG. 14D. These relays are to be energized upon the closing, respectively, of a "First Winding" drum switch 5732, a "Second Winding" drum switch 5733, a "Third Winding" drum switch 5734, a "Fourth Winding" drum switch 5735, a "Fifth Winding" drum switch 5736 and a "Sixth Winding" drum switch 5737 (all in FIG. 14D). It may also be noted in FIG. 14D that a "Last Winding" drum switch 5738 is associated with the last winding relay 422, mentioned previously.

The first winding relay 471 has normally open contacts 471A, 471B (both in FIG. 14E), 471C and 471D (both in FIG. 14G). Each of the other relays 472 through 476 has similar normally open contacts 472A through 476A, 472B through 476B (all in FIG. 14E), 472C through 476C and 472D through 476D (all in FIG. 14G), respectively.

A "ten terminal anchor level" relay 481 and a "twelve terminal anchor level" relay 482 (both in FIG. 14E) are associated with a "Y Anchor" drum switch 5712. The relays 481 and 482 are energizable upon the closing, respectively, of contact 411D of the ten terminal relay 411D of the ten terminals relay 411 and contact 412D of the twelve terminals relay 412. The ten terminal anchor relay 481 has a normal open contact 481A (FIG. 14G) and the twelve terminals relay 482 has a normally open contact 482A (also in FIG. 14G).

A "first Y terminal level" relay 491, a "second Y terminal level" relay 492, a "third Y terminal level" relay 493, a "fourth Y terminal level" relay 494, a "fifth Y terminal level" relay 495 and a "sixth Y terminal level" relay 496 are all illustrated in FIG. 14E. Associated with the six relays 491-496 are the "Y Anchor Pin" drum switch 5712, a "Y First Terminal Wrap" drum switch 5713, a "Y Wind" drum switch 5714, a "Y Second Terminal Wrap" drum switch 5715 and a number of contacts 5612, 5613, etc. of the programmable device 56 (FIG. 1) i.e., the card reader. The six relays 491-496 have corresponding normally closed contacts 491A (all in FIG. 14G).

A d.c. power source 497 for the distribution clutch 145 (FIG. 6), the distribution brake 202 (FIG. 7) and the rapid traverse clutch 201 is depicted in FIG. 14E. A "Distribution Brake On" drum switch 5710 (FIG. 14E)

will allow the operation of the distribution brake 202 when signalled by other control elements.

A d.c. power source 498 for the distribution clutches 128 and 129 (FIG. 7) is also depicted in FIG. 14E, as is another d.c. power source 499 for the spindles drive clutch 34 and the spindles brake 284 (both in FIG. 8). A "Spindles Brake On" drum switch 5705 (FIG. 14E) will allow the operation of the spindles brake 284 when signalled by other control elements.

A "tape cut time delay" relay 501 (FIG. 14F) is coupled for energization through the normally closed contact 456D (FIG. 14C) of the tape wrap relay 456 (FIG. 14C). The tape cut time delay 501, upon an appropriate time delay after energization, will function to open a normally closed contact 501A (FIG. 14F).

Five tension control brakes 502-506 are shown in FIG. 14F. Braking forces are to be regulated by five individually associated potentiometers 507-511 and an overall control autotransformer 512. Each brake 502-506 will govern the wire tension on a different one of the five spindles 31 (FIGS. 2 and 8).

Also illustrated in FIG. 14F are the five tape cut sole-noids 327 (see also FIGS. 13A-13D) and a normally open "Tape Cut" contact 280B of the counter 280 (FIG. 14G).

A pitch and distribution controller unit 521 (FIG. 14G) and a distribution relay operator 522 are associated with the X axis distribution reversal LVDT 179 and its control potentiometers 175 and 180. The pitch control LVDT 191, six control potentiometers 523-528 and the pitch and distribution controller 521 will regulate the pitch of each individual one of up to six coil windings on the five bobbins 21. The normally open contacts 471C-476C of the "first winding" through a "sixth winding" relays 471-476 (FIG. 14D) and the normally open contacts 458A-458C and 459A-459C of the auxiliary X anchor detent relays 458 and 459 (FIG. 14C) will cooperate to govern the operation of two "pitch" relays 531 and 532 and two "distribution" relays 533 and 534. The potentiometers 523-528 may be set to provide a desired pitch for each individual coil winding and the potentiometers 175 and 180 may be set to provide desired X axis distribution reversal points. The pitch and distribution controller 521 and the distribution relay operator 522 are conventional, commercially available voltage comparator means. The units 521 and 522 will compare voltage readings provided by the LVDT 179 or 191 with those preset into the respective potentiometers 175 and 180, or 523-528, as brought into operation by closure of the various contacts 458A-458C, 459A-459C or 471C-476C. Voltage comparison readings will serve to operate one or the other of the appropriate pair of relays 531 and 532 or 533 and 534, depending on the nature of a sensed "error" signal provided by the voltage comparison. The appropriate distribution control clutches or motor 48 will, thus, be operated toward attaining a "null" position of the apparatus, corresponding to a "zero error" reading by the pitch and distribution controller 521 or the distribution relay operator 522. Thus, the desired control over pitch and distribution will be attained.

The first pitch relay 531 has a normally open contact 531A (FIG. 14A) and a normally closed contact 531B (FIG. 14B). The second pitch relay has a normally

open contact 532A (FIG. 14A) and a normally closed contact 532B (FIG. 14B). The contacts 531B and 532B control the rotation and the direction of rotation of the winding pitch adjusting motor 48 (see also FIGS. 4 and 6).

The first distribution relay 533 has a normally open contact 533A and a normally closed contact 533B (both in FIG. 14D). The second distribution relay 534 has a normally closed contact 534A (FIG. 14D). These contacts are associated with energization of the relays 463 and 467 (both in FIG. 14D) to operate relay contacts which control the clutches 128 and 129 (FIGS. 4, 7 and 14E), the distribution clutch 145, the rapid traverse clutch 201 and the distribution brake 202.

A Y axis controller 541 (FIG. 14G) is generally similar to the pitch and distribution controller 521, functioning to energize one or the other of two "Y" axis" relays 542 and 543 (also in FIG. 14G). Six Y terminal level control potentiometers 544-549 may be preset to provide desired Y levels of the wire guides 36 for terminal wrapping on each bobbin terminal 27. Voltage signals from the Y level control LVDT 237 will be compared with voltage readings from the selectively sampled potentiometers 544-549. The sense of any departure from a "zero" comparison reading will govern which of the two Y axis relays 542 or 543 is energized.

The first Y axis relay 542 has a normally closed contact 542A and a normally open contact 542B (both in FIG. 14B). The second Y axis relay 543 has a normally closed contact 543A and a normally open contact 543B (also both in FIG. 14B). The contacts 542A and 543A control the direction of rotation of the Y axis drive motor 41 (FIGS. 4, 10 and 14B). The contacts 542B and 543B will generate a signal at a "Y-null" condition.

A ten terminal anchor level potentiometer 551 and a twelve terminal level potentiometer 552 are also shown in FIG. 14G. The selection of a potentiometer 551 or 552 will govern a Y anchor pin level of the wire guides 36 (FIG. 1), dependent upon the number of terminals 27 on each bobbin 21 (FIG. 3) to be wound by the apparatus, as directed by a suitable program card.

As indicated previously, the sequencing device 57 will actuate the various switches 5701A, 5701B, 5702, 5703, etc., in proper order such that the control circuit of FIGS. 14A-14G and 16 will operate the coil winding apparatus in accordance with instructions provided to the program-controllable device 56 and initial settings of the various control potentiometers of the apparatus. A suitable sequence of operations is provided by the pattern of switch actuations disclosed in FIGS. 15A and 15B.

55 The Operation of the Coil Winding Apparatus

In describing the operation of the coil winding apparatus, several assumptions will be made. Firstly, it is assumed that the apparatus is to be employed to produce transformers 22 with five windings as shown in FIG. 2. It is assumed, also, that five bobbins 21 of the ten terminal type shown in FIG. 3 have just been mounted, e.g., manually, each upon the wire spring member 32 of a different spindle 31. The spindles 31 are taken to be at rest and are assumed to retain the bobbins 21 with one set of five terminals 27 on each bobbin projecting generally toward an associated wire guide 36.

65 The detents 289 (FIG. 8) and 366 (FIG. 12) are taken to be at rest and are assumed to retain the bobbins 21 with one set of five terminals 27 on each bobbin projecting generally toward an associated wire guide 36. The detents 289 (FIG. 8) and 366 (FIG. 12)

presently occupy appropriate notches in the detent disc 286 and the detent plate 361, respectively, locking these detented elements in appropriate attitudes. The various carriages 37, 38, 39 are assumed to be at rest in correct initial positions and the wire guide Y level adjusting mechanism 381 (FIG. 5) to be in proper condition for the winding of transformers with ten terminals 27. Thus, each wire guide 36 is horizontally level with a first of the five terminals 27 on an associated bobbin 21. The winding pitch adjusting mechanism 47 is taken to be in an appropriate initial condition, the taping carriage 51 to be at rest in a withdrawn position (FIG. 13A) and the cutter rods 351 to be in extended positions. It is assumed, further, that several turns of each wire 23 have previously been wrapped about each associated anchor pin 352, either during a prior cycle of the apparatus or, if this is a first cycle, manually, and that each wire 23 is threaded through a different wire guide 36.

The X axis distribution and spindles drive motor 33 is taken to be presently energized. Such energization has occurred through a previous closure of the main switch 402 (FIG. 14A) and of the "On" switch 404 energizing the main relay 403 to close the contacts 403A, 403B and 403C. The program-controllable device 56 presently in the condition of FIG. 15A, Step 1. Thus the ten terminals relay 411 has been selected for energization through the closed drum switch contact 5702.

An operator now actuates the "Start Cycle" switch 417 (FIG. 14A) to close the contact 417A (Step 1 in FIG. 15A), providing power to the cycle control relay 416. Thus, the drum 57 is advanced to Step 2, initiating the automatic winding of five transformers under guidance from the previously described control system. Initially, the detent 366 (FIG. 12) is retracted from the detent notch 363 and the detent 364 is inserted into the notch 362 upon reversal of the drum switches 5706 and 5707 (see FIGS. 14B and 15A). The resulting displacement of the detent plate 361 along the X axis moves the wire guides 36 (FIG. 1) from positions in alignment with the anchor pins 352 into first terminal wrapping positions in alignment with the respective first terminals 27.

Orbital movement of the wire guides 36 about the first terminals 27 then begins. The Z axis orbital drive motor 43 (FIGS. 4, 7 and 14C) is energized through reversal of the condition of the "Terminal Wrap" drum switch 5722 (FIG. 14C). Thus, the crank mechanism 162 (FIG. 5) is rotated, operating various X carriage and Y carriage drive train elements linearly in the manner described above so as to provide harmonic X and Y axis components affording Z axis orbital movement of the wire guides 36.

The wire guides 36 orbit the respective first terminals 27 of the bobbins 21 to wrap a desired number of turns, e.g., two and one-half turns, of the wire 23 about each terminal. Such wire guide orbital motion ceases with the wire guides 36 each positioned in a wire winding position aligned with the terminal end of the central, recessed area 24 (FIG. 3) of the associated bobbin 21. At this stage, one section of wire 23 extends from each anchor pin 352 to the first terminal 27 of the associated bobbin 21, encircles the first terminal, and passes through the associated wire guide 36 back to various tensioning mechanisms and a source of the wire 23

such as a spool (not shown). Step 2 (FIG. 15A) has now been completed, as the drum 57 advances to Step 3.

The detent 364 (FIG. 12) is next removed from the 5 detent notch 362 and the detent 289 (FIG. 8) is removed from the detent notch 287 or 288. At the same time, the spindles brake 284 (FIG. 8) and the distribution brake 202 (FIGS. 4 and 7) are both engaged temporarily in order to avoid any unwanted movement. 10 The Z carriage drive mechanism, meanwhile, moves the wire guides 36 to an outermost Z limit position so as to provide adequate clearance during spindles rotation. The Y carriage drive mechanism moves the wire guides to a Y level approximately even with the respective bobbins winding surfaces. The spindles brake 284 and the distribution brake 202 (see FIG. 14E) are then released through operation of the relays 466 and 467 (both in FIG. 14D), while the spindles clutch 34 (FIGS. 4, 8 and 9), the distribution clutch 145 (FIGS. 4 and 6) and the forward-driving clutch 129 (FIGS. 4 and 7) are engaged. A fast wind operation, involving rapid rotation of the spindles 31, now commences under the control of the electronic counter 280 (FIG. 14G), the pitch 25 and distribution controller 521 and the speed control circuit (FIG. 16). Meanwhile, if the apparatus has been programmed for wire cutting due to a use of relatively thick wires 23, the wire cutters 351 (FIGS. 1 and 13A-13D) will be retracted momentarily to sever the 30 wires adjacent to the anchor pins 352. Absent a programmed wire-cutting operation, wire breakage of relatively thin wires 23 at the edges of the terminals will occur upon rotation, acting to sever the wires adjacent to the anchor pins. Step 3 (FIG. 15A) has now been completed, as the drum 57 advances to Step 4, at which time the anchor pins 352 are retracted (see FIG. 13B) to drop the scrap wire 23 into a suitable receptacle (not shown).

40 During the winding of a first coil of wire on each bobbin 21, rotation of the X axis distribution and spindles drive motor 33 (FIGS. 4 and 7) causes both rotation of the spindles 31 (FIGS. 8 and 9) and X axis reciprocation of the X carriage 38 (FIG. 5). Spindles rotation is provided through the rotating drive shaft 124 (FIGS. 7-9) and the engaged spindles clutch 34 (FIGS. 8, 9 and 14E). Reciprocation of the X carriage occurs through action of the X axis drive mechanism (FIGS. 5-7) upon engagement of the distribution clutch 145 45 and alternated engagement of the clutches 128 and 129 (FIGS. 7 and 14E), as directed by the pitch and distribution controller 521 (FIG. 14G) and distribution relay operator 522. The X axis distribution LVDT 179 (FIGS. 5 and 14E) continuously provides a varying 50 voltage signal to the pitch and distribution controller 521 (FIG. 14G) and distribution relay operator 522 to be compared with continuous voltage signals from the potentiometers 175 and 180. Alternated engagements of the clutches 128 and 129 (FIG. 14E), based upon 55 signal voltage comparisons, result from actions of the distribution relay operator 522 (FIG. 14G) to engage alternately the distribution relays 533 and 534. This, in turn, energizes and de-energizes the X extend relay 463 (FIG. 14D) in alternating manner to reverse the 60 conditions of the contacts 463B and 463C (both in FIG. 14E) which control the engagement and disengagement of the clutches 128 and 129. The speed ratio 65

between X axis motion of the wire guides 36 and rotations of the spindles 31 is determined by the previously set pitch adjusting mechanism 47.

Spindles rotation at a "fast wind" speed continues for a major portion of the winding operation. A "slow wind" speed is, however, employed when only a few turns remain to be wound. When the electronic counter 280 (FIG. 14G) reaches a preset value corresponding to such event, the counter adjusts the control system 465 (FIG. 16) for the eddy-current clutch 33A and the eddy-current brake 38B (FIGS. 4 and 7) to reduce the spindle speed from a "fast wind" speed condition to a "slow wind" speed condition. The eddy current clutch 33A is disengaged and the eddy-current brake 33B engaged briefly, causing the pulley 122 (FIGS. 4 and 7) to decelerate to the predetermined "slow wind" speed. Thereupon, the eddy-current clutch 33A is again engaged, causing the pulley 122 to rotate at the predetermined "slow wind" speed.

The reciprocating motion continues at reduced speed, maintaining the same ratio of X axis motion to spindles rotation, until the first coil winding operation is almost complete. A further signal from the electronic counter 280 then initiates a rapid traverse motion of the X carriage 38 to return the wire guides 36 to the terminal wrap X axis position. During such rapid traverse, spindles rotation continues while the clutch 129 (FIGS. 7 and 14E) is disengaged, the clutch 128 engaged, the distribution clutch 145 disengaged, and the rapid distribution clutch 201 engaged. Thus, the drive rod 206 (FIG. 7) moves the X carriage 38 so as to position the wire guides 36 adjacent to the bobbin terminals 27 at the end of the central recessed areas 24 of the bobbins. The rapid traverse motion continues until the inner distribution limit, provided for the LVDT 179 (FIG. 14G) as a reversal position, is reached, whereupon the rapid distribution clutch 201 (FIGS. 7 and 14E) is disengaged and the distribution brake 202 engaged.

Spindles rotation continues until the electronic counter 280 (FIG. 14G) senses the desired number of turns have been wound. The spindles clutch 34 (FIGS. 8 and 9) is then disengaged and the spindles brake 284 (FIG. 8) engaged. The eddy-current clutch 33A and brake 33B (FIG. 7) are adjusted to stop rotation of the pulley 122. The spindles drive train comes to rest. Step 4 is now completed, and Steps 5 and 6 follow.

After a brief pause at an otherwise idle Step 5 to allow stopping of the spindles 31, the spindles brake 284 and the distribution brake 202 are released; the spindles detent 289 (FIGS. 8 and 9) is inserted into notch 287 or 288 of the detent disc 286 and the detent 364 (FIG. 12) is inserted into the notch 367. Y carriage motion now moves the wire guides to a programmed second terminal Y level upon closure of the "Y Second Terminal Wrap" drum switch 5715 (FIG. 14E). Power is applied to one of the six Y terminal level relays 491-496, depending upon the program read by the program-controllable device 56. Any required Y level readjustment is provided by operation of the Y axis controller 541 (FIG. 14G), in the manner previously described, upon closure of one of the contacts 491A-496A. The Z axis drive motor 42, meanwhile, moves the wire guides to an inner limit of Z axis travel.

Orbital motion of the wire guides 36 to wrap sections of wire 23 about second terminals 27 of the bobbins 21 next occurs. The required Z axis orbital motion is once again provided by energization of the motor 43 (FIGS. 4, 7 and 14C) to wrap a desired number of turns, e.g., two and one-half turns, of the wire about each terminal. Wire wrapping ceases with the wire guides 36 located on the sides of the terminals 27 away from the central, recessed areas 24 (FIG. 3) of the bobbins. Step 6 (FIG. 15A) has now been completed, as the drum advances to Step 7.

The detent 364 (FIG. 12) is now withdrawn from the notch 362 and the detent 366 inserted into the notch 363, camming the detent plate 361 to shift the wire guides 36 into the X anchor pin position. Simultaneously, the tape carriage motor 52 (FIG. 8) is energized to move the tape carriage 51 from the position of FIG. 13B to the position of FIG. 13C, pressing the adhesive-coated tape 26 against the first winding on the bobbin 21 to adhere thereto. The drum 57 advances to Step 8 (FIG. 15A).

With the X anchor detent 366 (FIG. 12) positioned in the notch 363 the winding pitch adjusting mechanism 47 (FIGS. 4 and 6) prepares for the next winding. The winding pitch adjusting motor 48 (FIG. 6) is rotated if necessary, in a direction selected to reposition the pivot pin 157 (FIG. 6) at a desired height as indicated by a pre-selected one of the six preset 30 potentiometers 523-528 (FIG. 14G). Any required rotation is controlled by operation of the pitch and distribution controller 521 (FIG. 14G) as described previously.

If the apparatus has been programmed for wire cutting, the Y axis drive mechanism will now move the wire guides 36 vertically into positions approximately tangent to the upper surface of the spindles 31. The Z axis drive motor 42 (FIGS. 4 and 11) will cause the wire guides to move to the outer limit of Z axis travel. During taping rotations of the spindles 31, segments of the wire 23 will be wound around the portions of the terminals 27 which extend parallel to the spindles 31. These excess wire segments will be cut off by other apparatus (not shown) after all five transformers have been completely wound, taped and removed from the spindles.

If the machine has been programmed for wire breaking, the Y axis drive mechanism will instead move the 50 wire guides into position for wrapping wire around the anchor pins 352 (FIGS. 1 and 13A-13D), whereupon orbital wire guide motion will cause several turns of wire to be wrapped around the anchor pins. A section of wire 23 will then extend between a second terminal 55 27 of each bobbin and an associated anchor pin 352. Subsequent rotation of the bobbins 21 during taping will break the wires 23 adjacent to the sharp edges of the terminals 27 in the manner already described. Step 8 (FIG. 15A) has now been completed, as the drum 57 advances to Step 9.

The tape carriage 51 is presently in the position of FIG. 13C. The spindles detent plunger 289 (FIGS. 8 and 9) is now withdrawn from the notch 287 or 288. The spindles brake 284 is momentarily energized and then de-energized as the spindles clutch 34 is engaged and the drum 57 advances to Step 10 (FIG. 15A). The eddy-current drive control system 465 (FIG. 16)

operates the spindles drive mechanism to rotate the spindles 31 at a selected speed suitable for applying tape to the windings on the bobbins 21. The tape carriage 51 remains in its FIG. 13C position with the tape applying wheels 314 causing the adhesive-coated tapes 26 to continue to adhere to the rotating bobbins and windings until the bobbins have rotated approximately 180°. Then the tape carriage motor 52 moves the carriage 51 back into a position just past the actuation point of the switch 333 (FIG. 13D) where it remains for the remainder of the tape applying operation. Spindles rotations continue with tapes 26 under tension being wrapped around the windings until the electronic counter 380 generates a signal causing the tapes to be cut through energization of the solenoids 327. The solenoids 327 pivot the cutters 328 into the phantom line position of FIG. 13D cutting the tapes and holding the brushes 329 in position for wiping the loose ends of the tapes against the bobbins so that the tapes will adhere to the bobbin windings in a desirable manner. The electronic counter 380 (FIG. 14G) next signals a stop of spindles rotation. The spindles clutch 34 (FIGS. 8 and 9) is disengaged, the spindles brake 284 is engaged, the eddy-current drive control system 465 (FIG. 16) stops rotation of the pulley 122 (FIG. 7) and the drum 57 advances to Step 11 (FIG. 15A). The spindles detent plunger 289 (FIGS. 8 and 9) is again inserted into the adjacent detent notch of the detent disc 286, and the Y axis drive mechanism moves the wire guides 31 to correct Y level for the first terminal wrap of a second winding.

Steps 12 through 20 are substantially identical to Steps 2 through 10 described previously. The second coil winding and taping operation proceeds in the same manner as does the first. Subsequent coil winding and taping operations proceed in this same manner until a final winding and taping operation takes place. During this final operation, if the apparatus has been programmed for wire cutting, an anchor pin wrapping orbital movement of the wire guides 36 will occur prior to taping, a cutting operation occurring at the start of taping. After the last step, i.e., a return of the taping carriage 51 to its FIG. 13A position, of the final coil winding and taping operation, the completion of a cycle of transformer winding will be signalled by a cessation in operation of the apparatus and the lighting of a "Load Spindles" signal lamp 555 (FIG. 14C) both caused by a return of the "Drum Home" drum switch 5701A to its FIG. 14A condition (Step 1 in FIG. 15A) to unlatch the reset drum latch relay 423. A manual operator may now unload the five wound and taped transformers 22 (FIG. 2) from the spindles 31 and replace them with empty bobbins 21 (FIG. 3), preparatory to another operation of the "Start Cycle" switch 417 to commence another transformer manufacturing cycle.

It is to be understood that the above-described apparatus is simply illustrative of one embodiment of the invention. Many modifications may be made in accordance with the principles of the invention.

What is claimed is:

1. In an apparatus for winding wire convolutions to form successive coils about a bobbin having a plurality of radiating terminals wherein each coil is wound alternately with wrapping the wire about a terminal, the apparatus comprising:

means for mounting the bobbin to rotate about its axis;
 a wire guide for receiving the wire;
 means for sequentially advancing the wire guide into proximity with each successive terminal;
 means operated upon advance of said wire guide into proximity with each terminal for orbiting the wire guide about the proximate terminal to wrap the wire on the terminal;
 means operated upon each alternate wrapping of the wire on a terminal for moving the wire guide to overlay the bobbin;
 means rendered effective upon each movement of the wire guide into overlaying relationship with the bobbin for reciprocating the wire guide relative to the axis of the bobbin to distribute the wire along the bobbin;
 means rendered effective upon movement of the wire guide into said overlaying relationship for rotating the bobbin about its axis to wind convolutions of wire about the bobbin to form a coil prior to movement of the wire guide into proximity with the next successive terminal;
 pitch adjustment means, controlling the operation of the reciprocating means and variable incrementally through a continuous range of pitch-controlling conditions, for varying the rate of reciprocating movement of the wire guide to vary the pitch of the wound convolutions of wire through an infinite number of intermediate, incrementally varied pitch values; and
 means controlling the pitch adjustment means for setting a different but constant pitch value for each successive coil of wound convolutions.
 2. In an apparatus as set forth in claim 1, said reciprocating means including:
 a lever;
 means including a pivot pin for mounting the lever to pivot about said pivot pin;
 oscillatory drive means connected to a first axial location along the lever for pivoting the lever to oscillate about the pivot pin; and
 means connected between a second axial location along the lever and the wire guide and responsive to oscillatory movement of the lever for reciprocating the wire guide to distribute wire along the bobbin; and
 said pitch adjustment means including:
 means adjustable through a continuous range of operating positions for moving the pivot pin axially of the lever to vary the rate of reciprocation of the wire guide in response to oscillatory movement of the lever.
 3. In a mechanism for distributing a strand:
 a guide for the strand;
 a lever;
 means including a pivotal coupling mounted to move axially of the lever intermediate opposite ends of the lever for constraining the lever to oscillate about the pivotal coupling;
 means engaging the lever toward one end of the lever from the pivotal coupling for oscillating the lever about the pivotal coupling;
 means engaging the lever at a position across the pivotal coupling and toward the other end of the

lever from said one end and responsive to oscillating movement of the lever for reciprocating the strand guide in a linear direction, wherein said strand guide reciprocating means comprises;

an eccentric rotary member normally held fixed 5 against eccentric rotation about an axis extending perpendicularly to said linear direction;

first connecting means engaging the lever at said position for connecting the eccentric rotary member to be reciprocated along said linear 10 direction by oscillating movement of the lever;

second connecting means connecting the eccentric rotary member to the strand guide and responsive to movement of the eccentric rotary member along said linear direction for reciprocating the 15 strand guide in said linear direction;

means for rotating the eccentric rotary member about said perpendicular axis to impart to said second connecting means and to the strand guide a sinusoidally varying reciprocating movement in 20 said linear direction;

control means, selectively operable upon the rotating means, for initiating and terminating operation of the rotating means;

means engaging the lever constraining means adjacent the pivotal coupling for moving the pivotal coupling axially of the lever between the lever oscillating means and the strand guide reciprocating means; and 25

additional control means, selectively operable upon the pivotal coupling moving means, for regulating the axial position of the pivotal coupling along the lever.

4. In a strand distributing mechanism as set forth in 35 claim 3:

said lever constraining means including only a single pivot for the lever and constraining the lever to oscillate in a single plane about the pivot.

5. In a strand distributing mechanism as set forth in 40 claim 3:

said lever constraining means mounting the pivotal coupling to move linearly only in a direction axial of said lever.

6. In combination with the mechanism of claim 3: 45

third connecting means connecting the eccentric rotary member to the strand guide independently of said second connecting means and responsive to rotation of the eccentric rotary member about said perpendicular axis as controlled by said second 50 control means for imparting to the strand guide a sinusoidally varying translatory component of rotary motion of the eccentric rotary member in a direction normal both to said linear direction and to said perpendicular axis.

7. In the combination of claim 6: 55

said lever oscillating means, said pivotal coupling moving means and said eccentric rotary member rotating means each comprising a separate motor mounted remotely of the strand guide and fixed 60 against reciprocatory movement.

8. In a mechanism for distributing a strand:

a strand guide;

carriage means for mounting the strand guide to 65 move linearly along first, second and third mutually perpendicular axes and orbitally about said third axis;

first drive means including first motor means, mounted externally of the carriage means at a fixed position remote therefrom, for moving the strand guide linearly along said first axis;

second drive means including second motor means, mounted externally of the carriage means at a fixed position remote from the carriage means and from the first drive means, for moving the strand guide linearly along said second axis;

third drive means including third motor means, mounted externally of the carriage means at a fixed position remote from the carriage means and from the first and second drive means, for moving the strand guide linearly along said third axis;

fourth drive means including fourth motor means, mounted externally of the carriage means at a fixed position remote from the carriage means and from the first and second drive means, for orbiting the strand guide linearly about said third axis; and

control means, mounted externally of the carriage means at a position remote from the drive means and from the first, second, third and fourth drive means, for selectively operating the first, second, third and fourth drive means.

9. In a mechanism for distributing a strand as set forth in claim 8:

said fourth drive means including means operating portions of both said first and said second drive means in timed relationship in response to said control means for imparting mutually perpendicular components of motion to the strand guide along said first and second axes timed to orbit the strand guide about said third axis.

10. In a mechanism for distributing a strand as set forth in claim 8:

said first drive means including an eccentric rotary member held fixed against rotation during operation of the first motor means and connected to move the strand guide linearly along said first axis upon reciprocation of the eccentric rotary member along the first axis, said first drive means also including means rendered effective by operation of the first motor means as directed by the control means for reciprocating the eccentric rotary member along the first axis; and

said fourth drive means also including the eccentric rotary member and including means connecting the fourth motor means to the eccentric rotary member and responsive to the control means for rotating the eccentric rotary member as part of the operation of said fourth drive means to impart to the strand guide a sinusoidally varying reciprocatory component of movement along said first axis constituting one component of the orbital motion of the strand guide about said third axis.

11. In a mechanism for distributing a strand as set forth in claim 8:

said second drive means including a cam rotatable by the second motor means as directed by the control means and a cam follower connected to move the carriage means linearly along said second axis upon such rotation of the cam; and

said fourth drive means also including both the cam and the cam follower and including means responsive to the control means operating the fourth motor means for reciprocating the cam and the

cam follower together along said second axis sinusoidally to provide along said second axis a harmonic component of rotary motion of the carriage means about said third axis.

12. In a mechanism for distributing a strand as set forth in claim 8, at least one of the drive means comprising:

a driven member having a linear slot extending in a direction perpendicular to the axis of movement provided by said one drive means; 10
a rotary drive shaft having an eccentric portion extending along an axis of the shaft; means for mounting the rotary drive shaft to rotate about the shaft axis with the shaft axis extending perpendicularly both to the axis of movement provided by said one drive means and to the direction of the linear slot and with the eccentric portion passing through the slot; and means connecting the motor means of said one drive means to the rotary drive shaft and responsive to 20 the control means for rotating the rotary drive shaft about the shaft axis to move the driven member along the axis of movement provided by said one drive means.

13. In a mechanism for distributing a strand as set forth in claim 8, said carriage means comprising:

a strand guide supporting member having a pair of elongated toothed projecting elements extending parallel to one of said axes; means engaging the elongated projecting elements of 30 the strand guide supporting member for mounting the strand guide supporting member to move along said one axis; a shaft; means for mounting the shaft to rotate about an axis 35 extending substantially between the elongated projecting elements of the strand guide; and a pair of pinions mounted to the shaft with the teeth of each pinion enmeshed with the teeth of a different one of the projecting elements of the strand 40

guide.

14. In a mechanism for distributing a strand as set forth in claim 8:

normally inactive means associated with one of said drive means for varying the rate of movement of the strand guide in response to operation of the motor means of said one drive means; and fifth drive means selectively operable by said control means and including fifth motor means mounted externally of the carriage means at a position remote therefrom for activating and operating said rate varying means to vary the rate of movement of the strand guide in response to operation of the motor of said one drive means.

15. In a mechanism for distributing a strand as set forth in claim 14:

said one drive means comprising a lever connected to reciprocate the strand guide along the axis of movement provided by said one drive means upon pivotal movement of the lever and a pivotal coupling movable axially of the lever while mounting the lever to pivot about the coupling for reciprocating the strand guide; and said fifth drive means comprising means responsive to the control means for moving the pivotal coupling axially of the strand guide reciprocating lever.

16. In combination with a mechanism for distributing a strand as set forth in claim 14 to produce a wound article:

second normally inactive means for distributing another strand to a position adjacent the strand guide to be wound into the article; and sixth drive means selectively operable by said control means and including sixth motor means mounted externally of both the carriage means and the normally inactive means at a position remote therefrom for activating and operating said second distributing means to distribute another strand.
